UNITED STATES PATENT OFFICE.

EDGAR A. SPAULDING, OF PHOENIX, ARIZONA TERRITORY.

HARNESS-SADDLE.

SPECIFICATION forming part of Letters Patent No. 691,015, dated January 14, 1902.

Application filed October 23, 1900. Serial No. 34,018. (No model.)

To all whom it may concern:

Be it known that I, EDGAR A. SPAULDING, of Phoenix, in the county of Maricopa, Arizona Territory, have invented certain new and useful Improvements in Harness-Saddles; and I do hereby declare the following to be a full, clear, and exact description of the invention, such as will enable others skilled in the art to which it appertains to make and use the same.

This invention relates to certain new and useful improvements in harness-saddles; and it has for its object the production of a saddle of this character which will be simple in construction and at the same time be capable of perfect adjustment with relation to the back of a horse, whereby a maximum degree of comfort is obtained.

In carrying out my invention the pad-supporting plates are pivotally supported by the saddletree and held by suitable means at any desired angle or left to oscillate free, if preferred. The pads are secured to said plates by clamps, which are longitudinally adjustable therein. By means of this construction the pads are capable of both a pivotal and longitudinal adjustment with relation to the saddletree, thereby securing a perfect fit upon the back of a horse.

In the accompanying drawings, Figure 1 is a rear elevation of my improved harness-saddle. Fig. 2 is a plan view of one of the pads and its supporting-plates. Fig. 3 is a sectional view on the line 3-3, Fig. 2. Fig. 4 is a detail view of one of the rein-terrets. Fig. 5 is a view of a slight modification. Fig. 6 is a transverse sectional view illustrating the pivot-pins.

Referring to the drawings, 10 designates the saddletree, having its arm 11 provided with bifurcated ends 12 to receive the lugs 13 of the lug-plates 14, the arms *a* of said bifurcations being connected by a web *W*. Said lugs are formed of a lower base portion having opposite ears 35, provided with squared holes or openings *b*, coincident with corresponding holes or openings in said bifurcated ends, rods or bolts 15 being passed through said openings, whereby the said lugs and bifurcated ends are pivotally united. The rods or bolts 15 are squared at the point where they pass through ears 35, or they may be

provided with any other suitable non-pivotal connection. The bifurcated ends 12 are each provided with a boss or enlargement having 55 a central threaded bore 16, arranged to receive the threaded shank 17 of the rein-terret 18, the lower end of said shank being adapted to pass between the opposite ears of the lugs 13 and engage the pivot-pin 15, 60 whereby the plate 14 may be rigidly held at any desired angle with relation to arm 11.

The plate 14 is provided with a longitudinal recess 19, which is intended to receive the thill-tug-supporting strap 20, the skirt 21 coming flush with the under side of the plate 14 and strap 20. The pad 22 is made in any preferred form and of any suitable material, the same being held in position by a clamping-plate 23 passed thereunder. The latter is provided with internally-threaded bosses 24, designed to receive the threaded ends of bolts 25, which are passed through slots 26 in the lug-plate 14. By means of these slots and bolts the pad may be adjusted to fit horses of 75 various sizes, the clamp being tightened or loosened by turning the bolts 25 by means of a wrench or other suitable tool applied to the headed end of the same. The clamp-plate 23 is strengthened adjacent bosses 24 by means 80 of webs 28. It will be noted that when the clamp is tightened the same will cause the pad to fold around the edges thereof, forming a pocket which will effectually prevent the metal of said clamp from coming in contact 85 with the skin of the horse.

In practice the rein-terrets 18 are unscrewed and the pad 22 adjusted to the angle of the horse's back, after which the terret is again screwed down to prevent further movement. 90 The pad is also adjusted longitudinally by means of the bolts 25, being free to move in slots 26, whereby a perfect fit is obtained. After the adjustment is obtained the bolts 25 are tightened to prevent further movement 95 of the pad.

In Fig. 5 I have shown a slight modification of the terret. In this form the terret 29 is provided with a threaded recess to receive the shank 30 of an eyebolt 31. In practice 100 the shank 30 is passed through a suitable opening formed in the web *W* of the bifurcated ends 12, the pivot-bolt extending through the eyebolt 31.

From what has been said it will be observed that I have produced a harness-saddle which is exceedingly simple and inexpensive in construction and which is capable of perfect adjustment to fit the back of a horse, whereby a maximum degree of comfort is obtained when the pad is worn.

It will be particularly observed that by making the pads longitudinally adjustable on the pad-supporting plates in lieu of providing such adjustment between said plates and the saddle-tree I am enabled to obtain a more accurate and comfortable adjustment, the pads when so adjusted are more securely retained against displacement, the saddle-tree itself may be made much lighter and less cumbersome, and the use of unsightly adjusting bolts and plates is obviated.

I claim as my invention—

- 20 1. A harness-saddle comprising a saddle-tree, plates pivotally supported by said saddle-tree, and rein-terrets having members arranged to hold said plates against pivotal movement, as set forth.
- 25 2. A harness-saddle comprising a saddle-tree, pad-supporting plates, pivots uniting said saddle-tree and said plates, and means for engaging said pivots whereby said plates are held as against movement, as set forth.
- 30 3. A harness-saddle comprising a saddle-tree, pad-supporting plates, pivots uniting said saddle-tree and said plates, and rein-terrets having members arranged to engage said pivots, whereby said plates may be held against pivotal movement, as set forth.
- 35 4. A harness-saddle comprising a saddle-tree, plates having lugs pivotally supported by said saddle-tree, and rein-terrets carried by said saddle-tree and arranged to hold said plates as against pivotal movement, substantially as set forth.
- 40 5. A harness-saddle comprising a saddle-

tree having bifurcated ends, said ends being each provided with a boss or enlargement having a threaded bore, plates having lugs secured thereto, pivot-pins uniting said lugs and said bifurcated ends, and rein-terrets having threaded shanks working in said threaded bores, and engaging said pivot-pins, whereby said plates are rigidly held from pivotal movement in said tree, substantially as set forth.

6. A harness-saddle comprising a saddle-tree having bifurcated ends, the bifurcations of which are connected by a web having a boss or enlargement provided with a threaded bore, pad-plates, lugs secured thereto and having ears, pivot-pins uniting said lugs and said bifurcations, and rein-terrets having threaded shanks working in the bores of said bosses or enlargements, and engaging said pivot-pins, substantially as set forth.

7. A harness-saddle comprising a saddle-tree, pad-plates supported thereby, and provided with longitudinal slots, pads for each of said plates, clamping-plates passed under said pads, and threaded bolts passed through said slots and engaging said clamping-plates, substantially as set forth.

8. A harness-saddle comprising a saddle-tree, pad-plates supported thereby and provided with longitudinal slots, pads for each of said plates, clamping-plates passed under said pads, and provided with internally-threaded bosses, and threaded bolts passed through said slots and engaging said bosses, substantially as set forth.

In testimony whereof I have signed this specification in the presence of two subscribing witnesses.

EDGAR A. SPAULDING.
